UNITED STATES PATENT OFFICE.

WILLIAM E. FRANK, OF ST. LOUIS, MISSOURI, ASSIGNOR TO FOSTER BROTHERS MANUFACTURING COMPANY, OF ST. LOUIS, MISSOURI.

SPRING-BED.

No. 909,390.

Specification of Letters Patent.

Patented Jan. 12, 1909.

Application filed May 4, 1908, Serial No. 430,726. Renewed December 7, 1908. Serial No. 466,407.

To all whom it may concern:

Be it known that I, WILLIAM E. FRANK, of St. Louis, in the county of St. Louis and State of Missouri, have invented certain new and useful Improvements in Spring-Beds; and I do hereby declare that the following is a full, clear, and exact description thereof, which will enable others skilled in the art to which it appertains to make and use the same, reference being had to the accompanying drawings, and to the letters of reference marked thereon, which form part of this specification.

The object of my present invention is to provide a spiral spring bed of efficient construction which is simple, cheaply manufactured and capable of manufacture from cheaper material not permissible with good results in other constructions wherein equal efficiency is secured, and farther to provide a bed of spiral springs which is capable of maintaining an upright position of the springs under pressure and resisting a tendency to lop over sidewise in the bed as a whole.

Figure 1 shows a plan view of one corner of one surface of the bed of the present construction. Fig. 2 is a detail perspective view showing the form of springs and the relation of the parts. Fig. 3 is a perspective view of one of the springs employed in the construction.

Referring to the reference letters and figures in a more particular description, 1 indicates the spring employed in the construction which is of spiral form preferably with a reduced diameter of the convolutions at the center of the spring, but particularly provided with the tangential arms 1^a on the end convolution and projecting laterally substantially in the plane of the end convolution of the spring. These springs are arranged in the bed in longitudinal and lateral courses and are secured as to each course by the two longitudinal stay wires 2, 2 on each end of the spring or in each surface of the bed, and lateral stay wires 3 also on each end of the spring or in each surface of the bed. The stay wires 2 and 3 at their ends engage with and are secured to the border or frame wire 4, one of which is provided in the plane of each end of the spring and in the plane of each surface of the bed. The stay wires 2 are arranged substantially tangentially to the end convolution of each

spring and at each spring are provided with V-shaped hooks 5, which are passed under and around the end convolution of the spring from the inner side. The stay wire 3 passes diametrically across the end convolution of the spring and through the end of the V-shaped hook of the stay wires 2. In so doing the stay wires obtain a secure hold at diametrically opposite points of the end convolution of the spring, and the hook 5 having a relatively wide base engaging with the spring serves to resist a tendency to lop over when the spring is under compression more or less. The spring arms 1^a in each surface of the bed are extended to the next adjacent course of springs and at the end provided with a hook, which also engages in the V-shaped hook 5 of the stay wire before referred to, and is passed under the lateral stay wire 3, so that the arm is securely fastened to the next adjacent course of springs without employing any extra or additional fastening device.

It will be noted that the arm 1^a is passed under the stay wire 2 with which it comes in contact, assisting in maintaining the true vertical position of the spring under pressure. The arm 1^a is also of very material assistance in maintaining the spring in true vertical position, and it will be noted that the arm projecting from one end of the spring stands in substantially V-shaped relation to the arm projecting from the other end of the spring when viewed from a point in line with the spring. It will be noted also that there are no knots or sharp bends of any kind employed in the springs, which enables them to be produced from material of a brittle nature and not sufficiently ductile to be employed in springs having knots or sharp bends.

What I claim as new and desire to secure by Letters Patent is:

A spring bed consisting of spiral springs having tangential lateral projecting arms 100 at each end arranged in longitudinal and lateral courses in the bed, in each surface two stay wires to each course extending longitudinally and arranged tangentially to the end convolution of each spring and each 105 having at each spring a V-shaped hook engaging with the end convolution, in each surface a stay wire for each lateral course of springs crossing the end convolution of the springs diametrically and passing through 110

said V-shaped hooks, the said spring arms having hooked ends engaging in said V-shaped hooks at the next adjacent spring and retained under the lateral stay wires and wire border frames in the flange of the ends of the springs to which the said wires are attached, substantially as set forth.

In witness whereof, I have affixed my signature, in presence of two witnesses, this 17th day of April 1908.

WILLIAM E. FRANK.
